CLAIM

The ornamental design for a litter collector for attachment to dog collar, substantially as shown and described.

DESCRIPTION

FIG. 1 is a front elevational view of a litter collector for attachment to dog collar showing my new design, the broken lines are for purposes of illustration only and form no part of the claimed design.

FIG. 2 is a front elevational view thereof.

FIG. 3 is a right side, elevational left side identical view thereof.

FIG. 4 is rear elevational view thereof.

FIG. 5 is a top plan view thereof.

FIG. 6 is a bottom plan view thereof.

FIG. 7 is a right side elevational view of a second embodiment of FIG. 1; and,

FIG. 8 is a front elevational view of a third embodiment of FIG. 1, the front, side views, top, and bottom views being substantially the same as the embodiment of FIG. 1.
